UNITED STATES PATENT OFFICE.

PATRICK A. BAYLESS, OF OKLAHOMA, OKLAHOMA, ASSIGNOR, BY MESNE ASSIGNMENTS, TO SANITARY VACUUM STREET CLEANER COMPANY OF AMERICA, A CORPORATION OF SOUTH DAKOTA.

VACUUM STREET-CLEANER.

1,151,856.

Specification of Letters Patent. Patented Aug. 31, 1915.

Application filed November 22, 1911. Serial No. 661,702.

To all whom it may concern:

Be it known that I, PATRICK A. BAYLESS, a citizen of the United States, residing at Oklahoma city, in the county of Oklahoma and State of Oklahoma, have invented certain new and useful Improvements in Vacuum Street-Cleaners, of which the following is a specification, reference being had therein to the accompanying drawing.

This invention relates to vacuum street cleaners and has for its object the production of an efficient street cleaning machine wherein the dirt and other foreign matter may be drawn into the same, and the air readily discharged therethrough after having the foreign substance separated from said discharged air.

Another object of this invention is the production of efficient means whereby the brushes may accommodate themselves to the uneven surface of the ground over which the machine travels.

Of course, it will be obvious that other advantages will appear in the specification and claims, and further that the machine may be modified in its mechanical details without departing from the spirit of the invention.

In the drawings Figure 1 is a side elevation partly broken away. Fig. 2 is a top plan view with the dust receptacle in section. Fig. 3 is a vertical section taken through the suction casing. Fig. 4 is an enlarged detail longitudinal section of the lower end of the suction casing. Fig. 5 is a perspective of one of the vanes. Fig. 6 is a perspective of the brush supporting bar. Fig. 7 is a perspective of one of the brushes. Fig. 8 is a longitudinal section of one of the brushes. Fig. 9 is a transverse section of one of the brushes. Fig. 10 is a perspective view of one of the aprons. Fig. 11 is a transverse section through one of the vanes. Fig. 12 is a longitudinal section through the supporting bar of the brushes. Fig. 13 is a longitudinal section of the telescoping spacing bar carried by the aprons. Fig. 14 is a fragmentary sectional view showing the connecting means for the apron sections. Fig. 15 is a rear view of a series of aprons carried by the suction frame. Fig. 16 is a perspective view of one of the fabric strips attached to the bottom of the aprons. Fig. 17 is a perspective view of one of the baffle

plates. Fig. 18 is an enlarged detail of the hoisting mechanism for the vacuum chamber. Fig. 19 is a central transverse section through the vacuum chamber with the fan-mechanism removed. Fig. 20 is a detail perspective of the front of the vacuum chamber partly in section. Fig. 21 is a detail perspective of one end of the upper chain shield channel. Fig. 22 is a detail perspective of one end of the lower chain shield channel.

By considering the drawings, it will be seen that 1 designates the body of the vehicle which is supported in the usual manner upon wheels 2. The body of the vehicle may be formed of the usual construction of an automobile having the engine 3 placed in the front of the body of the vehicle. The main drive shaft 4 carries a drive gear 5 which meshes with the gear 6, coöperating with the transmission gear placed within the casing 7. The gear 6 also meshes with the drive gear 8 which gear coöperates with the raising mechanism for the vacuum casing. The main shaft 4 extends rearwardly for operating the fan propelling means. The vehicle body 1 carries a suction casing 9 intermediate its ends into which is slidably mounted an adjustable section 10. The suction casing as well as the adjustable section 10 extends the entire width of the machine so as to produce a wide cleaning surface. The 35 adjustable section 10 of the suction casing is provided upon one end thereof with a section 11, which carries upon each side thereof rollers 12, which rollers are adapted to engage the curb for furnishing a yieldable end for said 40 adjustable section of said suction casing in case the machine should come too near the curb. These rollers 12 are carried by the ears 13 formed upon the section 11.

The lower end of the adjustable section 10 tapers as is illustrated in Fig. 1 for forming a comparatively narrow suction opening along the lower edge of the suction casing. This tapered end of the adjustable section 45 comprises a curved, transversely extending strip 14, which is rigidly connected to the machine, and a plurality of hinged aprons 15. An auxiliary bar 16 is carried by the lower end of the transversely extending member 14 and also extends transversely of 50 the machine. A plurality of longitudinally extending sockets 17 are formed upon the inner face of the bar 16 and are adapted to

receive the auxiliary section 18 of the spacing bar which is also adapted to be connected to the aprons hereinafter described.

The auxiliary section 18 of the spacing bar is substantially T-shaped having its head portion 19 fitting in the sockets 17 carried by the plate or member 16. The primary section 20 is slidably mounted within said auxiliary section 18, and has its transversely extending head 21 positioned within the socket 15 carried by the aprons 15. Both the sockets 17 and 22 are provided with longitudinally extending slots 24 having pockets 25 formed centrally thereof for allowing the upward and downward movement of said spacing bar relative to said sockets. A plurality of these aprons 15 are employed and these aprons are hingedly connected to the lower end of the adjustable section 10. These aprons are each supported in place by divergent braces 26, the lower ends of which braces are supported by means of wheels 27. Brackets 28 depend from the lower edge of the adjustable section 10, and a bolt 29 passes through the lower end of each of these brackets 28, and has its forward end connected to one of the braces 26. A spring 31 is interposed between this brace and bracket for holding the aprons 15 in their correct position. It should be understood that each of the aprons is provided with these braces 26 and the wheels 27 for allowing the same to have individual movement. The inward movement of the aprons 15 is prevented by means of a strap 32 which is connected both to the apron and to the side of the adjustable section 10. The downward movement of the adjustable section 10 relative to the suction casing 9 is limited by means of a covering 33 which is connected both to the casing 9 and the adjustable section 10 as shown in Fig. 4. A thickened fabric web 34 is carried by the lower end of each apron 15 and is held in its vertical position by means of the spring 35 which will allow said fabric strip to yield provided the same should come in contact with any obstacles. The lower end of the adjustable section 10 is provided with a plurality of transverse supporting bars 36 from which depend brackets 37. The lower ends of these brackets 37 carry blocks 38. These blocks 38 are provided upon their adjacent faces with tongues 39 which engage the brush operating frame 40. The front edge of the brush operating frame travels in the block 38 similar to the one carried by the brackets 37 and this block engaging the front portion of the brush operating member is braced by means of the bracket 41.

The brush operating frame 40 is provided with a plurality of alined apertures 42 in which apertures work the bodies 43 of the brush. These bodies 43 are loosely mounted

within the apertures 42 for allowing the same to have a slight reciprocating motion therein. A frame 44 is carried near one end of the brush operating frame 40 and extends transversely thereof having a slot 45 formed therein in which works the angle end 46 of the crank rod 47.

One end of the brush operating frame 40 comprises a frame 48 which carries a coil spring 49. This spring 49 bears against the reduced end 50 of the brush operating frame and engages at its opposite end a reduced portion 51 of the auxiliary brush frame 52 of the brush operating frame 40. The frame 48 is provided with a plurality of longitudinally extending slots 53 in which travel pins 54 carried by the respective reduced portions 50 and 51. These pins 54 limit the movement of said reduced portions 50 and 51 within the frame 48 and the spring 49 will normally hold these reduced portions in their extreme position. The outer end of the auxiliary brush frame 52 of the brush supporting frame engages the hinge section 11 of the adjustable section 10, and normally holds this hinge section 11 in its upwardly extending position so that the same may be compressed when engaging a curb. The rod or shaft 47 extends vertically of the machine and carries a plurality of sprocket wheels 55. A shaft 56 is carried at the opposite end of the suction frame 9 and extends vertically thereof, and, like the shaft 47, carries a plurality of sprocket wheels 57. Sprocket chains 58 pass around the sprocket wheels 55 and 57 and a plurality of vanes or fan blades 59 are carried between the chains 58. These vanes or fan blades 59 are interposed between the rows of sprocket chains and are so connected as to allow the same to easily pass around the sprocket wheels. Therefore, it will be obvious that a continuous or endless chain of vanes or fan blades has been produced whereby a very powerful suction will be formed while said vanes are traveling.

Each of the vanes 59 comprises a scoop shaped body 60 which is corrugated longitudinally as at 61 whereby the same will be greatly reinforced. The lower edge of each vane 60 is provided with a transversely reinforcing cleat 62 which carries centrally thereof a lug 63, which lug is connected to the sprocket chain by means of a pin or other securing means 64. The forward end of the vane 60 is connected to the transversely extending portion 65 of the substantially V-shaped frame 66. This V-shaped frame 66 is provided with a foot 67, which foot is connected to the sprocket chain which is placed just above the vane 60.

From the foregoing description, and by giving Fig. 5 careful consideration, it will be obvious that since the vanes are inclined at an angle to the longitudinal axis of the

sprocket chain considerable air pressure will be produced when said chains are operated. It will be further obvious that since the vanes are only connected to the 5 series of chains at one point, these vanes will readily conform to the chain while passing around the driving sprocket wheels 55 and 57. The sprocket chains are arranged in two series, to wit an upper and 10 lower series, and each of the sprocket chains of each series is connected by vertically extending rods 68 for keeping said chains in alined position while traveling.

A gear 69 is carried by the main shaft 4, 15 and meshes with a beveled gear 70 which beveled gear is carried by a shaft 71. The shaft 71 carries at its opposite end a gear 72 which meshes with the gear 73 carried by the vertical shaft 47 for driving the 20 chains 58.

The frame of the sweeper carries a shaft 77, which shaft carries clutch gears 76, and these gears 76 are adapted to be operated by any suitable clutch mechanism for 25 throwing the same to an operative or inoperative position. The gears 76 are mounted upon a sleeve 116. An intermediate gear 75 is carried by the shaft 74 and is interposed between the gears 76 so as to allow the shaft 77 to be driven in different directions when engaging the respective gears 76. These gears 76 are shifted by means of an operating rod 117. The shaft 77 carries at each end a gear 82 which gears in turn mesh with gears 83 carried by longitudinally extending shafts 84, which shafts carry at their inner ends beveled gears 85 for rotating the shafts 86. These shafts 86 have their lower ends 30 positioned in a frame 87, and since these shafts 86 are threaded it will be obvious that the lower section of the suction casing will be raised and lowered through the 35 operation of said shafts.

The section 10 of the suction chamber or casing is made so as to allow the same to be raised and lowered so that the lower end of said adjustable section may be brought out of engagement with the pavement when it is not desired for the machine 40 to operate. The body 43 of the brush is provided upon its under surface with a longitudinally extending groove 88 into which fits the truss portion 89 of the U-bolt 45 90. This U-bolt is provided with a pair of upwardly extending arms having nuts 91 for holding the same in engagement with the body 43. A bolt 92 passes through the center of the body 43 and is provided with an eye 93 through which passes the truss portion 89 of the U-bolt 90. The bristles 94 which are preferably formed of wire, or other similar material, straddle the truss 50 portion 89 of the U-shaped bolt 90 and are clamped in engagement therewith by fit-

ting into the substantially V-shaped longitudinally extending slot 88. By drawing the U-shaped bolt tight within the slot 88, the bristles will take their usual position, that is to say, the outer bristles flaring 55 slightly outwardly as shown in Fig. 8. The body 43 of the block is provided centrally with a depending lug 95 through which lug extends the spacing member for the apron. By having the adjustable spacing 60 means for the apron connected to the brushes, it will be obvious that as the apron moves outwardly, these brushes will be moved upwardly within the brush operating 65 frame.

The aprons 15 are provided upon their side edges with flanges 96. A fabric sealing member 97 is connected to the aprons 70 by means of rivets 98. This fabric sealing member is loosely positioned around the flanges 96 so as to allow independent movement of the aprons and yet form an efficient seal between the different sections.

A refuse receptacle 99 is carried by the rear of the vehicle and this receptacle is 75 provided with a door 100 which is hinged thereto. This door is held in closed position by means of a catch 101. A plurality of transversely extending baffle plates 102 are carried by the refuse receptacle and 80 these baffle plates are arranged in vertical rows extending toward each other and overlapping so as to prevent the passing of the refuse between the same. These baffle plates are so spaced as to allow air to readily pass therethrough, but the spaces being 85 so small will, of course, prevent any refuse passing. The inner ends of the baffle plates 102 are bent as at 103.

As previously described and as illustrated 90 in Fig. 18 the frame 87 is supported by the brace 36. A nut 105 is loosely mounted upon the lower end of the shaft 86 for limiting the downward movement of the adjustable section 10 of the vacuum chamber and to prevent the lower adjustable section 10 from being injured by being 95 lowered too much.

Shield channels 106 are supported by the brace 34 and have angle ends 107 secured to the sides of the adjustable section 10. Shield channels 108 are provided with depending ends 109 which are secured to the adjustable section 10 as illustrated in Fig. 100 108. Both the channels 106 and 108 are provided with notches 110 for allowing room for the sprocket wheels which operate the fan carrying chains. It will be obvious 105 that the shield channels will form means for preventing the lateral swing of the chains 110 as the vehicle passes over rough ground. A set of channels are used for each of the upper and lower chains of each series of 115 the fan carrying chains.

The front apron 111 is carried by the 120

auxiliary bar 16. This bar 16 is secured to the curved strip 14 by means of bolts 112 working in slots 113 for allowing vertical movement of the front apron 111. The telescoping sections of the spacing bar allow the slight backward movement of the rear apron without interfering with the vertical movement of the front aprons and brushes.

By giving Figs. 2, 3 and 4 careful consideration it will be obvious that the material picked up off the street will be taken or drawn up through the center of the vacuum chamber. It will be further obvious that the vacuum mechanism is driven from the same engine as the trucks of the vehicle.

As the machine travels in a forward direction the vanes or blades 59 are caused to travel for the reason that the chains 58 are rotated through the medium of the sprocket 20 wheels 55. These vanes 59 will, therefore, cause a suction within the suction chamber 9 and cause the debris upon the surface of the street to be drawn into the suction chamber. The force of the suction created by 25 means of the blades 59 will drive the material, dust, etc., from the suction chamber into the rear of the machine which constitutes a reservoir for receiving the material sucked up by means of the vanes 59 through 30 the suction chamber. The baffle plates 102 will prevent the dust from passing out from the storage compartment or reservoir but will allow the air to be driven out from the top of the machine. These chains 58 are 35 driven through the medium of the main driving gear 69 coöperating with the gears 72 and 73 as illustrated in Fig. 3.

The brushes carried at the bottom of the suction chamber will brush the dirt or other 40 accumulations on the street so as to allow the dirt and dust to be acted upon by the suction from the suction chamber or casing. These brushes have a lateral reciprocating motion so as to allow the dirt upon the 45 street to be more easily severed from the surface of the street. The lower end of the suction chamber may be elevated so as to be brought out of engagement with the ground or surface of the street when so desired by 50 means of the gears 84 and 85 which co-operate with the rods 86 and frame 87, and it will, therefore, be seen that by means of this mechanism the machine may be thrown out of an operative position, that is to say, 55 the brushes will not be in engagement with the surface of the street. The gears 85 are driven by suitable mechanism previously described.

What is claimed is:—

60 1. In a device of the class described the combination with a vehicle, of a suction casing carried thereby and extending transversely thereof and having an adjustable lower section, brushes carried by said casing, means for raising and lowering said

adjustable lower section, a plurality of aprons carried by said adjustable lower section, means carried by said aprons, and co-operating with said brushes whereby said brushes will be raised when said aprons are 70 moved backwardly, and means for laterally moving said brushes within said adjustable lower end of said suction casing.

2. In a device of the class described the combination with a vehicle, of a suction 75 casing, means for creating a suction therein, yieldable aprons carried by the lower end of said suction casing, a brush operating frame, means for imparting lateral movement to said brush operating frame, 80 brushes carried by said brush operating frame, and means connected to said brushes and aprons whereby when said aprons are moved backwardly said brushes will be 85 raised.

3. In a device of the class described the combination with a vehicle, a suction casing carried thereby, a brush operating frame carried by said suction casing, said brush operating frame being provided with a plurality of sockets, brushes positioned within said sockets, said brush operating frame being provided with a transversely extending frame, said frame being provided with a longitudinally extending slot formed therein, and means working in said slot for reciprocating said brush operating frame.

4. In a device of the class described the combination with a vehicle, of a suction casing carried thereby, means for creating a 100 suction therein, a brush operating frame carried by said suction casing, an auxiliary brush frame secured to said brush supporting frame, a hinged section carried by one side of said suction casing and engaging the 105 outer edge of said brush operating frame, and rollers carried by said hinged section for preventing said hinged section from being injured when engaging a curb.

5. In a device of the class described the 110 combination with a vehicle of a suction casing, a brush operating frame carried thereby, said frame having a reduced extension at one end, a spring carrying frame passing over said reduced extension, an auxiliary 115 brush frame provided with a reduced portion extending within said spring carrying frame, a spring interposed between said reduced portion of said brush operating frame and the reduced portion of said auxiliary 120 brush frame, said spring carrying frame being provided with a plurality of slots, pins carried by said reduced ends and working in said slots, and means for reciprocating said brush operating frame.

6. In a device of the class described the combination with a vehicle of a suction casing, said casing tapering toward its lower end for forming a narrow suction opening, a bar carried by the lower edge of said cas- 130

ing, a plurality of aprons hinged to the lower end of said casing, adjustable spacing means for said aprons, said aprons being each provided with an enlarged socket extending transversely thereof, said bar being provided with a plurality of sockets, said adjustable spacing means comprising an auxiliary T-shaped section having its transverse head positioned within one of said sockets, 10 and a primary T-shaped portion positioned in the other of said sockets.

7. In a device of the class described, the combination with a vehicle, of a suction casing, a plurality of hinged aprons carried thereby, said aprons being provided upon each edge with a flange, said flanges of said aprons being adapted to fit snugly against each other, and a fabric sealing member straddling said flanges for forming a substantially closed wall and sealing the junction of said aprons.

8. In a device of the class described the combination with a vehicle, of a suction casing, said suction casing being provided with an adjustable lower section, means for driving said vehicle, said adjustable lower section being provided with transversely extending bars, upwardly extending brackets carried by said bars, a vertical shaft carried by said brackets, said shaft being threaded into said frame, a gear wheel carried by said shaft, and means coöperating with said drive mechanism of said vehicle for operating said shaft whereby said lower section of said suction casing may be raised and lowered.

9. A device of the class described comprising a suction casing provided with an adjustable lower section, a vertical raising shaft carried by the upper portion of said suction casing, means connecting said drive mechanism and said vertical shaft for rotating the same, a frame carried by said adjustable lower section, said vertical shaft being provided with a threaded lower end working in said casing, a nut carried by the lower end of said shaft for limiting the downward movement of said lower section, means for creating a suction positioned within said suction casing, and means operatively connecting said drive mechanism with said suction creating means to operate the latter.

10. In a self-propelled vehicle, the com-

bination with a truck, an engine carried thereby, an adjustable suction casing, means for creating a suction carried by said suction casing, and common means associated with said engine for driving said vehicle, driving said means for creating a suction and raising and lowering said adjustable suction casing.

11. A self-propelled vehicle comprising a truck, a suction casing carried thereby, a front apron carried by said suction casing, 65 said chamber being provided with vertical slots positioned therein, means carried by said apron working in said vertical slots for allowing the vertical adjustment of said front apron, rear aprons hinged to said suction casing, an expansible means connected to said rear aprons and front apron for allowing slight backward movement of said rear aprons without affecting said front apron.

12. In a self-propelled vehicle, the combination with a truck, of a suction casing, a refuse receptacle, a front apron vertically adjustable upon said vacuum casing, a rear apron hinged to said suction casing, 80 expansible means connecting said aprons, a brush interposed between said aprons, said expansible means passing through said brush for raising said front apron and swinging said rear apron backwardly when 85 said brush is elevated.

13. In a device of the class described the combination with a vehicle, of a suction casing provided with an adjustable lower section, said suction casing extending transversely of said vehicle, driving shafts carried by said vehicle within said suction casing, fan chains carried by said vehicle, sprocket wheels carried by said vertically extending shafts, said fan chains passing 95 around said sprocket wheels and capable of being driven thereby, and common means associated with said fan chains and said adjustable lower section of said suction casing for driving said fan chains and raising and lowering said adjustable lower section of said suction casing at a desired time.

In testimony whereof I hereunto affix my signature in presence of two witnesses:

PATRICK A. BAYLESS.

Witnesses:
